UNITED STATES PATENT OFFICE

BOWDEN WASHINGTON, OF NEW YORK, AND WILSON AULL, JR., OF ASTORIA, NEW YORK, ASSIGNORS TO REMOTROLE CORPORATION, A CORPORATION OF NEW YORK

RADIORECEIVER CONTROL

Original application filed June 13, 1927, Serial No. 198,470, now Patent No. 1,881,391. Divided and this application filed September 17, 1927, Serial No. 220,137.

This application is a division of our application Serial No. 198,470, filed June 13, 1927, and patented October 4, 1932, No. 1,881,391.

One object of our invention is to provide a simple and easy manner of turning on and off the filaments of a radio receiver from or near the loud speaker no matter where the latter may be located, and without causing a drop of filament voltage at the vacuum tubes which would be the case if the filament current was caused to flow through long extension wires of small cross section.

Another object is to be able to control from a point near the loud speaker the volume of the sound produced without spoiling the quality.

Another object is to turn on or off a receiver and control the volume of sound from a point remote from the receiver.

It is becoming more and more usual to use extension cords sometimes of considerable length in which case the listener has to go to the receiver to turn off the filaments. A particular instance of this may be given to show its usefulness in the broadcasting of "morning exercises". In this case the radio receiver would normally be placed in the living room, while the user might desire to take exercises in his own room or on a porch immediately upon arising. By means of our invention he could before retiring tune to the station which normally transmits the material for the morning exercises and bring the loud speaker to the exercising place. Upon arising at the predetermined hour he would light the filaments of his receiver from or at the loud speaker and adjust the volume to his pleasure, thus putting the set into operation, and upon finishing the exercises turn off the filaments without the necessity of going downstairs or into another room where the receiver is located.

Fig. 1 shows one form of our invention applied to a radio receiver having a so-called "filtered" output from which the direct current component of the plate current has been eliminated.

Fig. 2 is a diagrammatic representation of another arrangement of cord extension.

Fig. 3 is a detail view of another modification.

In the arrangement shown in Fig. 1 particularly intended for power amplifier tube output the plate 5 of the last audio frequency tube 6 of the set is connected in any suitable manner to a terminal 7. The filaments 8 are heated by a suitable source such as A battery 9. The anode current source or B battery 10 and the A battery in this case have a common terminal 11. The direct current from the anode battery is fed to the anode through the choke coil 12 while the alternating current or speech component passes through condenser 13. Relay coil 14 is interposed between the A battery and the terminal 15. The armature 16 and contact 17 constitute an automatic switch arranged to form a part of the filament circuit when the relay coil 14 is energized. Spring 18 tends to hold this circuit open.

The loud speaker telephone receiver 20 of any suitable type may have the usual cord 21 with terminals 22 and 23 for connection to the control unit 24. The latter has three terminals 25, 26 and 27 connected by conductors 28, 29, and 30 to the terminals 7, 11 and 15 respectively of the receiver.

A hand-operated switch has the stationary contact 31 and the pivoted switch arm 32 for opening and closing the circuit through the conductor 29, filament battery 9, relay coil 14, conductor 30 and pilot light 33. When this switch is closed the relay magnet 14 draws the armature 16 into contact with 17 and closes the filament circuit of the vacuum tubes of the set. The pilot light 33 serves as a silent signal that the filament battery is "on". The conductors 28, 29 and 30 may be contained in a single cord extension.

In order to control the volume of the loud speaker a potentiometer may be provided with its resistance 35 connected across the leads 28 and 29 of its slider arm 36 connected to the loud speaker. By moving this arm 36 any desired fraction of the total voltage available may be applied to the loud speaker 20.

By this arrangement the volume of the loud speaker signals may be varied without 100

appreciably affecting the operation of the tubes or the efficiency of the receiver.

For convenience in operation the arms 32 and 36 may be connected for instance by a link 37 so that the control of volume and the opening and closing of the energizing circuit may be effected by a single instrument.

When the switch arm 32 is swung off the contact 31, the relay 14 is deenergized and the spring 18 opens the filament circuit and thus turns off the set. It is assumed of course that the receiver will have suitable amplifying and detecting means and that tuning to the desired frequency will be done in any suitable manner.

The control unit may be embodied in the base of the loud speaker as shown in Fig. 3 with a knob 38 for operating it in any well known manner.

The relay 14 and its switch element may be embodied in the receiver itself or sold as a separate article of manufacture for connection to any set. The control elements for the filament and for the speaker volume may be embodied in a unit provided with a cord for attachment to the receiver as shown and the usual speaker and cord can be plugged into it or otherwise connected in the same manner as into the usual receivers.

To avoid having two cables connected to the control unit as shown in Fig. 1 we may run the three wires 28, 29 and 30 through the loud speaker casing 40 as shown in Fig. 2 to the control unit 41. These three wires together with the two usual loud speaker wires 21 constitute a single cable for convenience in installation.

Where we have used the terms "A battery" 40 "B battery" "filament source" "plate source" or "anode source" in the claims, we, of course, intend to include any suitable source of current.

65

We claim:

1. Means for controlling a radio receiver having vacuum tubes and a loud speaker, said means consisting of a relay having contacts for opening and closing the complete cathode heating circuit of said receiver, said relay being adapted for operation from the cathode heating source, a control box having a voltage divider provided with a manual control and adapted to control the input to said loud speaker, and a switch in the operating circuit of said relay connected for operation by the manual control of said voltage divider. 75

2. Apparatus for controlling a vacuum tube radio receiver having a loud speaker from a distance comprising a relay, at least one multiple conductor cable, and a control unit having a voltage divider and a switch, said relay being controlled by said switch and connected so as to establish and stop effective current flow in all power circuits of said receiver, means of connection between the switch and the voltage divider whereby said switch may be actuated by the movable element of said voltage divider and suitable cable connections between said receiver, said control unit, and said loud speaker. 85 35 90

3. In a vacuum tube radio receiver, a loud speaker, a switch connected to the loud speaker, means for automatically opening all filament heating circuits independently of the B battery and independently of the loud speaker circuits when said switch is open, means at the loud speaker for controlling its volume independently of the filament circuit, and connecting leads between the receiver and the loud speaker with its control means, at least one of said leads being common to the loud speaker control circuit and the filament control circuit. 95 100 105
